US00D563546S

(12) **United States Design Patent** (10) Patent No.: **US D563,546 S**
Lulla et al. (45) Date of Patent: ** *Mar. 4, 2008

(54) **DEVICE FOR INHALATION**

(75) Inventors: **Amar Lulla**, Mumbai (IN); **Geena Malhotra**, Mumbai (IN)

(73) Assignee: **Cipla Limited**, Maharashtra (IN)

(**) Term: **14 Years**

(21) Appl. No.: **29/242,264**

(22) Filed: **Nov. 8, 2005**

(30) **Foreign Application Priority Data**

May 9, 2005 (IN) 199371

(51) LOC (8) Cl. 29-02

(52) U.S. Cl. D24/110

(58) **Field of Classification Search** D24/110;
128/203.15, 203.21, 200.14, 200.23, 205.24
See application file for complete search history.
